Term of patent 14 years

(Cl. D34—5)

Fig. 1.

Fig. 2.

To all whom it may concern:

Be it known that I, Paul Berkowitz, a citizen of the United States, residing at Newton, in the county of Middlesex and Commonwealth of Massachusetts, have invented a new, original, and ornamental Design for a Game Spinner, of which the following is a specification, reference being had to the accompanying drawing, forming a part thereof.

In the drawing:

Fig. 1 is a front view of a game spinner, showing my new design; and

Fig. 2 is an edge view thereof.

Fig. 1 of the drawing is shaded to indicate color contrast.

The dominant features of my new design are shown in solid lines in the drawing.

I claim:

The ornamental design for a game spinner, substantially as shown and described.
